UNITED STATES PATENT OFFICE.

WILLIAM WAIT, JR., OF GARDEN CITY, NEW YORK, ASSIGNOR TO CURTISS AEROPLANE & MOTOR COMPANY, INC., A CORPORATION OF NEW YORK.

WHEEL CHOCK FOR AEROPLANES.

Application filed April 9, 1924. Serial No. 705,188.

My invention relates to wheel chocks for aeroplanes.

The customary practice, in the operation of an aeroplane, is to chock the wheels of the landing gear as a preliminary step. Usually a wooden block, a stone, or some similar obstruction is employed. Having chocked the wheels, the motor is started and allowed to run anywhere from two to ten minutes until thoroughly warmed up; the pilot or operator having meanwhile entered the machine. Everything being satisfactory, either an attendant or the pilot himself, (if the pilot—necessitating that he climb out of and again into the machine), removes the chocks and throws it or them to one side; the aeroplane thereupon proceeding upon its way. Because of the bulk, size and weight of the ordinary chock, no one heretofore has seen fit to carry it or them along with or within the machine.

Now it often happens during flight, and more particularly during cross country flying, that an enforced landing is required to be made. If, under such circumstances the motor is stopped (either intentionally or otherwise), in order to again proceed, it immediately becomes necessary to re-chock the wheels of the aeroplane, and since wheel chocks are not an item of aeroplane equipment, obviously a great deal of inconvenience, and often damage, is encountered in again getting under way.

The object of the present invention is to avoid the inconveniences and disadvantages above noted. Instead of utilizing a fixed chock of wood or other heavy material, a flexible chock, foldable when not in use, light, compact and strong, is used. Preferably it is so formed and constructed as to occupy, when folded, a minimum of space, and may readily be carried along as an item of standard equipment for any and all types of land machines. When used, the strip of flexible material is fastened at one end to the aeroplane, its opposite end being carried over the forward periphery of and under the landing gear wheel. To prevent slippage, that part or portion of the flexible strip which engages the ground may be, if desired, provided with one or more cleats. Moreover, if desired, suitable chock release mechanism operable from a point within the fuselage or body of the aeroplane, may be installed.

Other advantages of the invention will be hereinafter pointed out.

In the drawings, wherein like reference characters denote like or corresponding parts.

Fig. 1 is a perspective view of an aeroplane showing the application of the chocks.

Fig. 2 is a front elevation of a portion of the landing gear of an aeroplane showing one wheel properly chocked, and

Fig. 3 is a side elevation of that portion of the aeroplane illustrated in Fig. 2.

In the embodiment of the invention selected for illustration an aeroplane 10 of more or less conventional type is shown. Said aeroplane includes an upper supporting surface 11, a lower supporting surface 12, a power plant 13, a propeller 14, and a landing gear 15, the latter being of the V-strut type including wheels 16, symmetrically arranged at opposite sides of the fore and aft axis of the machine. Within the fuselage or body of the aeroplane an operating wheel 17 is mounted. Preferably the wheel 17 is in convenient proximity to the pilot's seat. Said wheel (see Fig. 3) is mounted on a shaft 18 journalled in one of the diaphragms of the fuselage, which shaft, on the opposite side of the diaphragm, carries a drum 19 over which operating cables 20 are trained. Said cables 20, at a point directly beneath the drum 19, and within the fuselage, are carried over pulleys 21 to extend right and left therefrom into the wings comprising the lower supporting surface 12. The opposite ends of the cables 20 are fastened as at 22 to bolts 23 spring pressed as at 24 and mounted in suitable guides 25 carried inside the lower wings. The arrangement of the springs 24 is such that the bolts 23 are at all times urged outwardly.

The wheel chocks per se, one for each wheel, are of identical construction. Each comprises a flexible band or strip of canvas 26 which, when the chocks are in use, extend over the forward periphery of the landing gear wheels 16 and well therebeneath as indicated. Throughout the ground engaging portion of each strip 26 one or more transversely extending cleats are provided. Each strip at its opposite ends is releasably fastened by means of an eye-end connection 28 to the bolts 23 aforesaid.

With the wheel chocks placed as indicated, a clockwise rotation of the wheel 17, simul-

taneously withdraws both bolts 23 from the connection 28. Assuming at this moment that the propeller 14 is furnishing sufficient forward thrust to propel the machine in a forward direction, obviously the flexible strips 26 will immediately flatten out and thereafter permit the machine to move in a forward direction until entirely clear of the chocks. When clear, the motor may then be throttled down, the chocks picked up, folded and placed within the machine, after which the pilot may proceed on his way. In folding the chocks the flexible strips 26 may either be rolled or folded flatwise to occupy a minimum of space.

While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

What is claimed is:

1. A wheel chock for aeroplanes including a flexible strip, the free end of which is carried rearwardly beneath the landing gear wheel and the opposite end of which is carried upwardly and over the forward periphery of said wheel, together with means

for fastening the upper end of said strip to the aeroplane at a point behind the transverse vertical plane of the axis of rotation of said wheel.

2. A wheel chock for aeroplanes including a flexible strip adapted to extend over the forward periphery of and well beneath the landing gear wheel, said strip throughout the ground engaging portion of its length being provided with one or more cleats. 3b

3. A wheel chock for aeroplanes including a flexible strip adapted to extend over the forward periphery of and well beneath the landing gear wheel, together with means for fastening said strip, at one end, to the aeroplane, in combination with means carried by operable form within aeroplane to release said fastening means and thru such release shed the wheel chock entirely clear of the aeroplane. 4b

4. In combination, an aeroplane, separate chocks for the wheels of the aeroplane fastened at one end to the aeroplane wings, and means extended into the aeroplane wings and operable from within the aeroplane to release the wheel chocks simultaneously. 5b

In testimony whereof I hereunto affix my signature.

WILLIAM WAIT, JR.
